UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS SONS & MAXIM LIMITED, OF WESTMINSTER, ENGLAND.

FIRING-GEAR OF ORDNANCE.

994,982.

Specification of Letters Patent. Patented June 13, 1911.

Application filed March 20, 1909. Serial No. 484,746.

To all whom it may concern:

Be it known that we, ARTHUR TREVOR DAWSON and GEORGE THOMAS BUCKHAM, both subjects of the King of Great Britain, residing at 32 Victoria street, Westminster, in the county of London, England, have invented certain new and useful Improvements in and Relating to the Firing-Gear of Ordnance, of which the following is a specification.

This invention relates to firing gear of the kind in which there is at the breech end of the gun a firing plunger which operates through a firing lever and other appropriate mechanism to release the firing pin or striker mounted in the usual manner in a sliding lock casing carried by a box slide attached to the axial vent. The firing plunger is released by the pulling of the usual trigger and is cocked by the angular movement of the breech screw in opening the breech, through the intervention of a cocking cam on the breech screw. According to our invention the said firing plunger is provided with a tripping piece or cam which is so arranged relatively to the firing lever that operates the push rod on the box slide for liberating the striker for firing the gun, that the said tripping piece or cam clears itself of the firing lever after imparting sufficient movement to the latter for actuating the push rod and firing the gun, whereby the various moving parts are permitted to return to their normal position under the influence of their springs and the firing plunger is rendered free to be recocked.

In order that our said invention may be clearly understood and readily carried into effect we will describe the same more fully with reference to the accompanying drawings in which:—

Figure 1 is an elevation of our improved firing gear looking toward the breech of the gun. Fig. 2 is a side elevation of the same as seen from the left of Fig. 1. Fig. 3 is a sectional plan, the parts being shown in the position they occupy prior to the release of the firing plunger from its cocked position for firing the gun. Figs. 4 and 5 are sectional plans of the firing plunger showing it and its tripping cam in the position they occupy during and after the operation of the firing lever. Fig. 6 is a sectional plan of a modification of the firing plunger and

its tripping cam. Fig. 7 is a sectional elevation of the trigger mechanism which is arranged on a non-recoiling part of the gun mounting. Fig. 8 is a sectional plan of the same, and Fig. 9 is a transverse section taken approximately on the line 1—1 of Fig. 7.

A is the breech end of the gun.

B is the flange of the breech screw to which the cocking cam B' is attached.

C is the swinging carrier.

D is the sliding lock casing and D' the box slide in which said lock casing moves in the well known manner. The said lock casing is provided with the usual striker which is actuated by the trigger sear D² controlled by the trigger D³, the said trigger being mounted on the axis pin of the trigger lever D⁴ which, when the lock casing is in the firing position, lies with its free end contiguous to the inner end of the spring push rod D⁵ carried by the box slide.

E is the firing plunger which is mounted to slide in a bracket F secured to the rear face of the gun.

H is the releasing lever which is pivotally connected at h to a block F' mounted in the bracket F and retained therein by a split pin f². I is the firing lever which is pivotally mounted at i in an extension of the carrier C. J is a rocking spindle, one end of which is furnished with a radial projection or lug J' that lies adjacent to the said releasing lever H and the other end of which is furnished with an arm J² that lies contiguous to the trigger K which is pivotally mounted at k in the pistol grip K' and which operates the said arm J² as will be herein-after described.

The aforesaid firing plunger E is hollow to receive the tripping piece or cam E' and a spiral spring e, the tripping cam being connected to the plunger by a transverse axis pin e³, and having a shoulder e⁴ against which a loose plug e⁵ bears under the influence of the spring e. The end of the plunger remote from the tripping cam has two hooked portions e² which, when the plunger is in its fully retracted or cocked position, engage with similar hooked portions h² on the releasing lever H as shown in Fig. 3. The engagement of these two hooked portions e² h² retains the firing plunger cocked and a notched or recessed portion e⁶ of the

tripping cam E' in engagement with the contiguous end i' of the firing lever I as shown in Fig. 3. The said firing plunger may also be provided with a handle E² (Figs. 1 and 2) or other cocking device for enabling it to be recocked by hand as required. The spring e rests mainly in the hollow of the firing plunger E, but the outer end rests in a recess in the block F'. It operates the loose plug e⁵ at one extremity and the loose plug f³ at the other extremity. This plug f³ transmits the spring pressure to the releasing lever H.

When the breech is being opened to charge the gun, the angular motion of the breech screw in the direction of the arrow in Fig. 1 in unlocking, causes the cocking cam B' on the flange of the breech screw, to press the firing plunger outward from the position shown in Fig. 5 to that shown in Fig. 3, thus cocking said firing plunger by bringing its hooked portion e² into engagement with the hooked portion h² of the releasing lever H. As the notched portion of the tripping cam E' on the plunger passes the adjacent or outer end i' of the firing lever I, the tripping cam is partially rotated on its axis e³ anti-clockwise against the resistance of the spring e thereby passing the lever without disturbing it, owing to the fact that the spring i³ offers greater resistance than the spring e. Immediately the notch e⁶ comes opposite the end i' of said lever the said notch engages therewith by the reaction of the spring e as shown in Fig. 3. The breech mechanism having been unlocked and the firing plunger thus fully cocked, the carrier C is swung open carrying with it the firing lever I and the operation of loading is performed in the usual manner. On the carrier being closed again the firing lever I resumes the position in which its end i' reengages with the notch e⁶ of the tripping cam E' (Fig. 3). When the releasing lever H is operated for example by the arm J' on the rocking spindle J (Fig. 7) forming part of the mechanical arrangement for firing the gun, the hooked portion h² of the said releasing lever is disengaged from the hooked portion e² of the firing plunger, whereby the latter is released and urged forward by its spring e. During this forward movement of the plunger its tripping cam (by reason of its notch e⁶ being still engaged with the adjacent end i' of the firing lever I) is caused to turn on its axis e³ in a clockwise direction against the resistance of its spring e, thereby pushing this end i' of the firing lever outward as shown in Fig. 4. The other arm i² of the firing lever that lies in contact with the firing bolt or push rod D⁵ on the box slide of the lock, thereby actuates the said push rod and effects the firing of the gun through the aforesaid trigger lever D⁴ in the usual manner. As the said

firing plunger E completes its forward movement under the influence of its spring e, the shoulder e^x on the left of the said notch e⁶ of the tripping cam slips past the end i' of the firing lever and the tripping cam turns about its axis pin e³ in an anti-clockwise direction by the action of its spring plug e⁵, thus resuming its normal position shown in Fig. 5. At the same time the firing lever, after having effected its firing movement as aforesaid, at once returns to its normal position under the action of its spring i³ and the spring push rod D⁵. The tripping cam is then ready to reengage with the end i' of the firing lever as shown in Fig. 3, when the firing plunger is again acted upon by the cocking cam B' at the next angular displacement of the breech screw in unlocking it.

In this arrangement of firing gear the action of the firing plunger is controlled by one spring; the parts are simple in construction and are easily assembled; the complete arrangement is an unobtrusive feature on the gun, having no large projections likely to interfere with the free working of the gun; all the springs in the arrangement are in a free or unrestrained condition when the gear is not in use, thereby obviating undue stress on the parts; and it is impossible to release the striker while re-cocking of the firing plunger is being effected by means of the aforesaid cam on the breech screw thereby insuring safety in the use of the apparatus.

In the modification shown by Fig. 6, the position of the said tripping cam E' is not changed by the action of the spring plug e⁵ which merely bears against the adjacent semi-circular surface thereof under the influence of the spring e and gives rise to sufficient friction between these parts to prevent the said cam from changing its position on the axis pin e³ unless positively moved. The said tripping cam has a toe piece e⁷ which protrudes through a slot in the firing plunger and lies in a slot f in the surrounding bracket F. When the firing plunger is in the cocked position (which is the position in which it is represented in this figure) the toe piece abuts against the end f' of the said slot f. When the firing plunger is released by disengaging its hooked portions e² from the hooked portions h² of the releasing lever H and flies forward under the action of the spring e, as in the preceding arrangement already described, the notched portion e⁶ of the said tripping cam engages with the adjacent end i' of the firing lever and moves the latter about its pivot i to a sufficient extent to fire the gun, the shoulder e^x of the tripping cam getting in front of the said end i' of the firing lever as the firing plunger completes its forward movement. The firing lever then resumes its original

position under the influence of its spring i^3 and in so doing returns the said tripping cam to its housed position in the firing plunger. When the said firing plunger is 5 cocked again by the cocking cam during the angular movement of the breech screw in unlocking, the shoulder e^x of the tripping cam will ride over the end i' of the firing lever without actuating the latter and as the 10 said firing plunger assumes its fully cocked position the toe-piece e^x of the tripping cam will come against the end f' of the slot f , whereby the said tripping cam will be moved into the position shown in this figure (Fig. 15 6) with its notched portion e^x ready to engage with the firing lever at the next release of the firing plunger in the manner already explained.

The mechanism for actuating the releasing lever H may be of the kind illustrated by Figs. 7 to 9, in which K' is a pistol grip forming the rear portion of a hollow casing K^2 which contains the electric contacts $k' k^2$ and which is carried by a bracket K^3 attached to the gun cradle. The forward portion of the casing is connected with a neck K^4 on the said bracket by means of a hinged jaw or clamp K^5 provided with a suitable clamping screw K^6 . The said casing K^2 is 20 prevented from moving around the bracket by a key K^7 engaging with the neck of the bracket, endwise movement of the said casing on the neck being prevented by a segmental key K^8 on the hinged jaw or clamp. 25 The trigger K is contained in the pistol grip K' and is provided with an insulated button k^9 , through which the contact lever k^4 is depressed for closing the electric contacts to fire the gun. The trigger is also provided with a roller k^5 through which is 30 actuated the forward arm J^2 of the rocking firing spindle J that conveys motion to the releasing lever H to liberate the firing plunger E and fire the gun as above described. All of the internal parts are readily 40 accessible for inspection or adjustment from the top of the casing K^2 which is normally closed by a cover plate K^9 and securing screw K^{10} .

50 What we claim and desire to secure by Letters Patent of the United States is:—

1. In firing gear for breech loading guns, the combination of means for releasing the firing pin or striker, a transverse firing plunger, means for retracting and cocking said plunger, means for releasing said plunger from its cocked position, and a hinged tripping piece operatively interposed between said plunger and the said 55 striker-releasing means, said tripping piece engaging with the striker-releasing means when the plunger is cocked, and operating to clear itself from engagement with said striker-releasing means after actuating the latter.

2. In firing gear for breech loading guns, the combination of means for releasing the firing pin or striker, a transverse firing plunger, means for retracting and cocking said plunger by the angular displacement 70 of the breech screw, means for releasing said plunger from its cocked position, and a hinged tripping piece operatively interposed between said plunger and the said striker-releasing means, said tripping piece 75 engaging with the striker-releasing means when the plunger is cocked, and operating to clear itself from engagement with the striker-releasing means after actuating the latter.

3. In firing gear for breech loading guns, the combination of a firing lever forming part of the means for releasing the firing pin or striker, a transverse firing plunger, means for retracting and cocking said plunger, 80 means for releasing said plunger from its cocked position, and a hinged tripping piece operatively interposed between said plunger and the said firing lever, said tripping piece 85 engaging with the firing lever when the plunger is cocked, and operating to clear itself from engagement with the firing lever after actuating the latter.

4. In firing gear for breech loading guns, the combination of a firing lever forming 95 part of the means for releasing the firing pin or striker, a firing plunger, means for retracting and cocking said plunger, means for releasing said plunger from its cocked position, a tripping piece pivoted to said plunger, said tripping piece engaging with the firing lever when the plunger is cocked, and on the release and advance of the plunger, turning about its pivot in actuating the 100 firing lever and then disengaging itself ready to resume its reengaging position.

5. In firing gear for breech loading guns, the combination of a firing lever forming part of the means for releasing the firing pin or striker, a firing plunger, means for retracting and cocking said plunger, means for releasing said plunger from its cocked position, a spring controlled tripping piece pivoted to said plunger, said tripping piece under the influence of its spring engaging with 115 the firing lever, and on the release and advance of the plunger, turning about its pivot against the resistance of its spring and in so doing actuating the firing lever and then under the influence of said spring disengaging 120 itself from the firing lever and resuming its reengaging position.

6. In firing gear for breech loading guns, the combination of a firing lever forming part of the means for releasing the firing pin 125 or striker, a firing plunger, a spring mounted therein, means for retracting and cocking said plunger, means for releasing said plunger from its cocked position, a tripping piece pivoted to said plunger and acted on by the 130

1
 plunger-spring, said tripping piece under the influence of the plunger-spring engaging with the firing lever and on the release and advance of the plunger, turning about its pivot against the resistance of said plunger-spring and in so doing actuating the firing lever and then under the influence of said plunger-spring disengaging itself from the firing lever and resuming its reengaging position.

7. In firing gear for breech loading guns, the combination of a firing lever forming part of the means for releasing the firing pin or striker, a firing plunger, a spring mounted therein, means for retracting and cocking said plunger, means for releasing said plunger from its cocked position, a tripping piece pivoted to said plunger and formed with a notch for engagement with the firing lever, a shoulder on said tripping piece, and a loose plug bearing against said shoulder under the action of the plunger-spring.

8. In firing gear for breech loading guns, the combination of a firing lever forming part of the means for releasing the firing pin or striker, a firing plunger, a spring mounted therein, means for retracting said plunger, a hooked portion at the inner end of said plunger, a releasing lever for engagement therewith under the action of said plunger-spring, means for actuating said releasing lever, a tripping piece pivoted to said plunger, the said tripping piece engaging with the firing lever under the influence of

the plunger spring when the plunger is 35 cocked, and on the release and advance of the plunger, turning about its pivot in actuating the firing lever and then disengaging itself ready to resume its reengaging position.

9. In firing gear for breech loading guns, the combination of the firing lever forming part of the means for releasing the firing pin or striker, a firing plunger, a spring mounted therein, means for retracting said plunger by 45 hand and by the angular displacement of the breech screw, a hooked portion at the inner end of the plunger, a releasing lever for engagement therewith under the action of said plunger spring, a rocking firing spindle actuated by the firing trigger, a lug on said firing spindle situated contiguous to the releasing lever, a tripping piece pivoted to said plunger, the tripping piece engaging with the firing lever under the influence of the 50 plunger-spring when the plunger is cocked, and on the release and advance of the plunger, turning about its pivot in actuating the firing lever and then disengaging itself ready to resume its reengaging position.
